TRAVEL GAME WITH NON-LOSABLE PARTS

Anthony D. Boulanger, 51 Euclid Ave.,
Ridgefield Park, N.J.

Filed June 19, 1957, Ser. No. 666,672

1 Claim. (Cl. 273—145)

My invention relates to game boards employing movable parts. The main feature of my invention is in the novelty of non-losable parts. All moving parts necessary to the action of the game are attached and cannot be lost or mislaid.

Many games may be played at a table or some level plane to prevent parts from sliding off the board or slipping out of position but in my construction the game may be played on almost any plane—on a couch—in a car—and other irregular levels.

I represent further that the stay-on-parts are new and novel in themselves. A particular new and novel feature is the transparent plastic box attached flexibly to the game board permitting an oscillation of the box at a touch of the finger. Enclosed and sealed within the box is a cubical block, each face of a different color, preferably red, white, blue, green, yellow and one face marked with a Zero. At a flip of the finger, the box will bounce around and cause a variation in colors upon which the action of the game depends.

Secondly, and a further object is to provide simple means to score the points without using a separate pad and pencil. This is accomplished by a row of beads or counters mounted slidably on a chain or cord fastened at each end to terminals on the board. Each player slides a counter over to his side as he makes a point.

Thirdly, and a further object is to provide non-losable pegs to mark the progress of the game. This is accomplished by fastening the pegs to the game board by a flexible cord or bead chain long enough to reach any hole along the track of the game.

It will thus be seen that I have provided a compact device for playing certain board games with the feature of non-losable parts.

To more clearly set forth my invention, I have shown the preferred embodiment of the device. However, I do not wish to be restricted to the details of construction actually shown herein, but reserve the right to make changes in minor respects without departing from the essential design in which the invention resides. In particular another form of the invention is the substitution of an ordinary die for the color block. The game would then proceed by count instead of color. The same track design and rules would apply and the same means of scoring points.

On the drawings:

Fig. 1 is a top view of the device.

Fig. 2 is a cross section taken along line 2—2 of Fig. 1.

Fig. 3 is a cross section taken along line 3—3 of Fig. 1.

Fig. 4 is a view of the cubical Color Block 15 representing each face in a different color, preferably red, white, blue, green, yellow and one face Zero, shown in the drawing as 15a, 15b, 15c, 15d, 15e, and 15f.

In the form of the invention shown in Fig. 1, the board 10 is conveniently oblong to accommodate the preferred design of the game. 11 and 12 are eyelets in

2

the board, in five different colors as hereinafter shown. 13 is the transparent plastic box to which the piece of foam rubber 14 is cemented to the box 13 and the board 10. 15 is the Color Block within the transparent box. 5 16 are the blocks fastened to the board to limit the side swing of the box. 17 and 18 are track pegs attached to chains 17a and 18a which are attached to the board 10 at 19 and 20. 19, 20, 33 and 34 are the points of attachment to the board 10. The chains pass through 10 the board at these points and are fastened on the underside. 21, 22, 23, 24, 25, 26, 27, 28, 29 and 30 are track markers to indicate destinations and are colored eyelets in series of five different colors to match the five colors of the Color Block 15, Fig. 4. Continuing Fig. 1, 15 31 is a travel peg in one of the holes. 32 is a travel peg shown in position for the start of the game. 31a and 32a are chains to which the travel pegs are attached. 35 and 36 are the starting points for each of the two players. 37, 38 are green, 39, 40 are red, 41, 20 42 are blue, 43, 44 are white, 45, 46 are yellow and are so represented according to patent regulations and show positions along the line of travel. 39a and 40a show various destinations. 41a and 42a are positions at which players score points. 25 45 and 46 are points at which players have to go back to start. 45a and 46a are points at which players have to go back to junction as indicated in the play of the game shown hereinafter. In Fig. 2 and Fig. 3, 50 is the cord along which the counters 47, 48, 49 are 30 strung. 51 and 52 are end clips to which the cord is attached by fasteners 53 and 54. 55 is a strip of wood fastened lengthwise along the board to support the counting device. 56 and 57 are rubber pads cemented to the underside of the board to raise it and allow sufficient space for the pegs to go through to the proper depth. The game is for two players and proceeds as follows: At the beginning of the game, each player inserts his travel peg 31 and 32 in his respective starting point 35 and 36. The player at the right then flips the box 13, 40 and the color turned up by the color block 15 will determine his track color, number and destination. He then inserts the top peg 17 at the extreme left of the track indicated and must leave it there as a guide to his destination. He cannot choose his own destination but 45 must travel to the one indicated, for example, if he flips blue, he is required to go to Chicago, track 3, color blue and he places the top peg 17 at that point 25. The player on the left then flips the box and finds his destination in the same manner inserting the peg 18 as 50 his guide at 22, 24, 26, 28 or 30 depending upon the color turned up. Having found their respective destinations, the travel starts. Player at right takes a second flip and starts his travel following the colors along the main line guided by the colors turned up at his turn. 55 Using his travel peg 31, he follows the colors in successive order to his junction and turns into his track shown by the guide peg 17. In his travel he meets with obstacles and credits shown on the board, for instance if he strikes yellow at 45 he goes back to start. 60 At 41a he takes points shown on the board but if he strikes a yellow 45a along the numbered tracks he goes back to junction and tries again at his next turn. Upon reaching destination, as for example, Chicago at 39a he has finished that trip and takes a point. He slides the 65 points made during the course of the travel to his side of the scoring device shown in Fig. 2. He then removes both pegs and flips the box to determine his new destination and begins again at start 35 following the same procedure as before until the game is ended. In 70 his turn player at left follows in the same manner of play until the game is ended. Each player takes one turn at a time but at green immediately preceding destina-

tion, he may take three turns to reach destination. On zero, player misses that turn. Player to first reach large center ball at 48, Fig. 2, wins the game.

Having described my invention, what I believe to be new is:

A device affixed to a game board comprising a transparent box with a die enclosed therein, in combination with a block of resilient material having parallel end surfaces, one of said surfaces being connected to the box and the other of said surfaces being attached to the board, said block and box having aligned side planar surfaces at right angles to the end surfaces in further combination with a pair of guides affixed to the board parallel to and slightly spaced from the device, whereby the device can oscillate in one direction.
